UNITED STATES PATENT OFFICE

IRWIN COHN, OF NEW YORK, N. Y.

DESIGN FOR A DOLL

Application filed April 14, 1931. Serial No. 39,477. Term of patent 3½ years.

To all whom it may concern:

Be it known that I, IRWIN COHN, a citizen of the United States, residing in New York, county and State of New York, have invented a new, original, and ornamental Design for a Doll, of which the following is a specification, reference being had to the accompanying drawings, forming part thereof.

Fig. 1 is a front elevation of a doll, showing my new design.

Fig. 2 is a side elevation thereof.

I claim:

The ornamental design for a doll, as shown.

IRWIN COHN.
